UNITED STATES PATENT OFFICE

EDWIN ARCHER TURNER AND CHARLES J. SURDYKOWSKI, OF PITTSBURGH, PENNSYLVANIA, ASSIGNEES, BY MESNE ASSIGNMENTS, TO THE STANDARD STOKER COMPANY INC., OF NEW YORK, N. Y., A CORPORATION OF DELAWARE

LOCOMOTIVE STOKER

Application filed July 18, 1927. Serial No. 206,427.

This invention relates to locomotive stokers of the type wherein conveyors bring the coal from the tender to the locomotive and raise it to a suitable elevation for scattering over the grates, and has for its principal objects to simplify the structure, to reduce the number of parts, to reduce the distance the coal must be elevated and to provide a small compact organization that can be readily applied to locomotives, both old and new, with a minimum of obstruction in the cab and which will endure the rigors of service.

Further objects and advantages of the invention will appear as the description is read in connection with the accompanying drawings illustrating the preferred embodiment of the invention, and in which

Fig. 1 is a vertical section through the stoker and portions of the tender and the locomotive taken on the broken line 1—1 of Fig. 2;

Fig. 2 is a plan view of the rear portion of the stoker and a section of the forward portion thereof and parts of the locomotive taken on the line 2—2 of Fig. 3; and

Fig. 3 is a rear elevation of the stoker and parts of the locomotive, the transfer conduit being cut away on the line 3—3 of Fig. 1.

But this specific illustration and the correspondingly specific description are used for the purpose of disclosure only and are not intended to support a narrow and limited construction of the claims.

In its general organization the stoker includes a transfer conveyor, or tender unit generally indicated by A in Figs. 1 and 2, an elevating and distributing mechanism or locomotive unit generally indicated by B, and a driving mechanism generally indicated by C.

A portion of the locomotive tender is indicated at 10, including a deck 11 provided with a slot 12 through which the fuel descends to the transfer conveyor under the control of a plurality of sliding plates 13 which may be shifted to make the delivery from the tender at a point suited to the conditions of the supply.

The rear end of the fire box of the loco-

motive is indicated at 14 equipped with grates 15, extending forwardly from a back head 16 which has a firing opening 17. Projecting rearwardly from the back head is a cab 18 having a seat deck 19 and a firing deck 20.

The transfer conveyor or tender unit is composed of rear and forward portions which, while separable, are in fact, one continuous transfer conveyor.

The rear portion includes a trough 21 made fast beneath the deck on the tender in position to receive fuel through the slot 12 and lying substantially along the center line of the tender. Mounted within the trough is a transfer screw 22 extending lengthwise and serving to move the coal along the trough towards the locomotive and cooperating with a crusher bar 23 to reduce large lumps to a size suitable for firing.

At its rear end the screw 22 is provided with a socket 24, polygonal in cross-section, which receives and cooperates with a projection 25 of similar cross section on a stub shaft 26 which projects through the rear end 27 of the trough into a gear casing 28 and is equipped with a gear 29 driven by a pinion 30 mounted in a lateral extension 31 of the gear casing 28.

At its front end the trough is equipped with a hollow coupling element 32, having a spherical portion 33, equipped with a flange 34 fixed to a similar flanged ring 35 having a spherical portion 36 receiving a spherical portion 37 on a coupling element 38, whereby a universal connection is formed.

The coupling element 38 forms a part of the forward portion of the transfer conduit, which includes also a tube 39 fixed to the element 38 by bolts 40 and having its forward end slidably received in a conduit section 41, having a spherical ring 42 at its forward end received in a socket of like shape formed by a flange 43 on the base of the locomotive unit and a flanged ring 44 secured thereto, whereby a universal connection is effected between the forward end of the transfer conduit and the locomotive unit.

The base of the locomotive unit is a substantially cylindrical casting 45 having a bracket 46 on its forward side by which the base is made fast to the mud ring 47 of the back head 16. The flange 43 projects rearwardly from the base casting 45 and provides communication with the transfer conveyor, as just described.

The upper portion of the base casting 45 terminates in a flanged nipple 48 upon which is bolted or otherwise secured a substantially cylindrical conduit 49, which extends along the back head substantially parallel to the upright center line of the locomotive. The cylindrical portion of the base casting and the conduit 49 make up the elevator casing; and, in this instance where the back head is inclined forwardly, this casing is correspondingly inclined and extends along the back head at one side of the firing opening 17.

The fuel is raised in the elevator by an elevating screw 50 equipped at its lower end with a sealing ring or dust guard 51 and a stub shaft 52, which latter projects through the bottom 53 of the elevator casting into a gear housing 54, where it is equipped with a beveled gear 55 by which it is driven.

The elevator may deliver the coal at any suitable height, either to the hand firing door 17, or any other opening that may be desired. In this preferred embodiment the upper end of the conduit 49 is equipped with an elbow 56 which serves to turn the fuel laterally and downwardly into a delivery conduit 57 from which it drops on a ridge plate 58 and passes in more or less separate streams to chutes 59 which direct it onto a distributor plate 60 from which it is scattered over the grates by jets of steam issuing from the nozzle box 61 which is supplied by pipes 88 (Fig. 2).

As shown, the upper end of the conduit 49 is equipped with a flange 62 to which a similar flange 63 on the elbow 56 is bolted. The other end of the elbow has a flange 64 bolted to a corresponding flange 65 on the delivery conduit 57. The lower end of the conduit 57 has a flange 66 bolted to a box 67 which, in turn, is secured to the back head 16 by bolts 68 passing through the flange 69 (Fig. 1). The front side of the box 67 is entirely open and the rear side is provided with an opening 70 corresponding to the hand firing opening 17.

The construction of the chutes 59; their mounting in the box 67, and their operation may be substantially the same as disclosed in the Hanna Patent No. 1,497,014 of June 10, 1914. In the interest of brevity particular description is omitted.

Power to drive the stoker is generated by a motor 71 (Fig. 2), preferably including a plurality of cylinders 72 and a crank shaft

73, which latter lies substantially parallel to the center line of the tender. At each end the crank shaft is equipped with a universal joint 74, one of which drives a rearwardly directed shaft 75 projecting into the rear gear casing and receiving the pinion 30. The other universal joint drives a shaft 76 directed forwardly and downwardly to a universal joint 77 (Fig. 1) connected with a shaft 78 mounted in the gear casing 54 and carrying a beveled gear 79, meshing with the gear 55. The shaft 78 also projects through the housing 54 and is equipped with a crank 80 to furnish power for driving the mechanism for swinging the chutes 59.

Operation

The fireman, by shifting the plates 13, will provide an opening in the bottom of the tender at a convenient point for the coal to descend by gravity into the trough 21. The screw 22 propels it along the trough, through the forward section of the conveyor 39, and delivers it directly against the elevating screw 50 with sufficient pressure to facilitate its elevation by that screw and overcome the tendency of the coal to rotate with the screw without rising.

The coal passes up the elevator into the elbow 56, turning laterally and downwardly through the delivery conduit 57 onto the ridge plate 58, which divides it into two streams, each of which is received by the corresponding chute 59 and passed onto the distributor plate 60. The chutes may be moved back and forth from left to right in unison, or otherwise, in the well known manner to play the streams of coal on the distributor plate, from which the steam jets scatter it over the grate.

By making the elevator extend parallel to a substantially vertical plane at one side of the firing opening, the distance necessary to raise the coal is reduced as compared with an arrangement in which the elevator is inclined to a vertical plane.

It is also within the contemplation of this invention that the coal may be delivered through an opening other than the hand firing opening, and distributed by any suitable means, such, for example, as the distributor tube disclosed in the patent to Lower, No. 1,455,058.

The lateral inclination of the forward portion of the transfer conveyor increases slightly the distance the fuel must travel from the tender to the elevator, but the resistance is much less in a horizontal conveyor than in an elevator, and this slight increase of distance makes a negligible difference in the operation.

By mounting the engine in the intermediate position and driving the two conveyors by oppositely directed shafts connected to

opposite ends of crank shafts, a drive mechanism of extreme simplicity is produced. The whole organization is very simple, easy and cheap to produce, and efficient in operation.

5 By locating the engine in a horizontal position instead of vertically a relatively large two-cylinder reversible engine may be mounted in a protected position within the clearance lines of the locomotive.

10 We claim:

1. In a stoker for use and in combination with a locomotive including a backhead having a firing opening leading into the firebox and a tender behind the locomotive, the combination of a substantially upright single elevator arranged at one side of the center line of the locomotive, and delivering to the firing opening, a transfer conduit for bringing fuel from the tender to the locomotive and including a rear portion located substantially along the center line of tender and a forward portion lying at an angle to the rear portion and extending 20 in a direct line from the forward end of the rear portion to the base of said elevator and delivering directly thereto, said forward portion being disposed laterally from and at an acute angle with a vertical plane through the center line of the tender, and means for advancing fuel through the conduit.

2. In a stoker for use and in combination with a locomotive including a backhead having a firing opening leading into the firebox and a tender behind the locomotive, a single elevator rising from a point at one side of the center line of the locomotive and extending along the backhead to a point adjacent to the firing opening and delivering thereto, and a transfer conveyor bringing fuel from the tender to the locomotive and including a rear section located substantially along the center line of the tender and a forward section for conveying fuel from the rearward section to the elevator and being universally jointed to each, and lying at an angle to the center line of the locomotive, an elevating screw in said elevator, an engine located alongside the transfer conveyor, a driving shaft operatively connected with the engine and operatively connected with the transfer conveyor at its rear end and a second driving shaft operatively connected with the engine, and gearing connecting the second driving shaft with the elevator screw.

3. In a stoker for use and in combination with locomotives including a back head having a firing opening leading into the fire box and a tender behind the locomotive, a single elevator rising from a point at one side of the center line of the locomotive and extending along the back head substantially parallel to the vertical center line and de-

livering to the firing opening, a transfer conveyor bringing fuel from the tender to the locomotive and including a rear section located substantially along the center line of the tender and a forward section universally connected with the forward end of the rear section and the elevator and delivering thereto and lying at an angle to the center line of the locomotive, an elevating screw in said elevator, an engine located in a horizontal position alongside the transfer conveyor, a driving shaft extending rearwardly from the engine and operatively connected with the engine and with the transfer conveyor at its rear end and a second driving shaft extending forward from the engine and operatively connecting the engine with the elevator screw.

4. In a stoker for use and in combination with a locomotive including a backhead having a firing opening leading into the firebox and a tender behind the locomotive, a single elevator rising from a point at one side of the center line of the locomotive and extending upright along the backhead substantially parallel to the vertical center line and closely adjacent to one side of the firing opening and at its upper portion opening inwardly at and delivering fuel to a side of the firing opening above the lower marginal edge thereof, a transfer conveyor bringing fuel from the tender to the locomotive and including a rear section located substantially along the center line of the tender and a forward section flexibly connected with the forward end of the rear section and the base of said elevator and delivering directly thereto, said forward section extending in a straight line from the forward end of the rear section to the base of said elevator and being disposed laterally from and at an acute angle with a vertical plane through the center line of the tender.

In witness whereof we affix our signatures.

E. ARCHER TURNER.
